Int. Cl. D7—04

U.S. Cl. D81—10

FIG. 1

FIG. 2

FIG. 3

FIG. 4

FIG. 5

FIG. 6

FIG. 1 is a perspective view of an outdoor gas grill embodying our new design;

FIG. 2 is a front elevational view;

FIG. 3 is a side elevational view, both sides being identical;

FIG. 4 is a rear elevational view;

FIG. 5 is a top plan view; and

FIG. 6 is a bottom view.

The design of this invention is characterized by the configuration of the front, sides and top of the case, as shown more clearly in FIGS. 1, 2, 3 and 5, and by the configuration of the handles, as shown in all of the views. The base, shown fragmentarily and in broken lines, is included for illustrative purposes only.

We claim:

The ornamental design for an outdoor gas grill, as shown and described.
